UNITED STATES PATENT OFFICE.

JAMES G. WILKIE, OF BROOKLYN, NEW YORK.

ATTACHMENT FOR GAS STOVES.

Application filed December 9, 1922. Serial No. 605,805.

To all whom it may concern:

Be it known that I, JAMES G. WILKIE, a citizen of the United States, and residing at Brooklyn, in the county of Kings and State of New York, have invented certain new and useful Improvements in Attachments for Gas Stoves, of which the following is a specification, such as will enable those skilled in the art to which it appertains to make and use the same.

This invention relates to gas stoves, burners, or the like and particularly to attachments adapted to be detachably mounted in connection with the tops of gas stoves of different kinds and classes; and the object of the invention is to provide an attachment of the class specified, which is designed to concentrate the flame and the heat arising from the flame of a burner or a number of burners directly to the bottom face of a pot or vessel placed over such burners; a further object being to provide the top face of the attachment with a number of projecting members, upon which a pot or vessel is placed, to form a slight air space between the bottom of the pot or vessel and the top face of said attachment; a further object being to provide the attachment or the aperture or apertures thereof which register with the burner or burners of a gas stove with members which are adjustable inwardly and radially of said apertures to form supports for smaller pots or vessels; a still further object being to provide a plurality of resilient members by means of which the attachment may be firmly held in position in connection with the top of a gas stove, and by means of which the shifting of said attachment on the stove is obviated; and with these and other object in view, the invention consists in an attachment of the class and for the purpose specified, which is preferably stamped from sheet metal, and which is simple in construction, efficient in use and constructed as hereinafter described and claimed.

The invention is fully disclosed in the following specification, of which the accompanying drawing forms a part, in which the separate parts of my improvement are designated by suitable reference characters in each of the views, and in which:

Fig. 1 is a plan view of one form of my improved attachment indicating the different methods of its use.

Fig. 2 is a longitudinal central section

through the device as shown in Fig. 1 and indicating in dotted lines a section through a two-burner gas stove with the attachment mounted in connection therewith; and,

Fig. 3 is a partial section on the line 3—3 of Fig. 1 on an enlarged scale.

In Fig. 2 of the drawing, I have indicated in dotted lines a section of a two-burner gas stove 5, the burners being indicated at 6 and 7 and at 8 is indicated the rim portion of the framework of the stove and 9 represents the usual rib-work at the top of the separate burners 6 and 7 of the stove upon which it is usually the custom to place cooking pots, vessels or the like, and at 10 I have shown one form of my improved gas stove attachment.

My improved attachment 10 as shown in the accompanying drawing is oblong and rectangular in form and is preferably stamped from sheet metal and comprises a top plate 11 having downwardly directed side and end walls 12, a central partition wall 13 and centrally of the opposite end portions of the top 11 are formed two apertures 14 and 15 having downwardly and outwardly flaring walls 16 as clearly shown in Figs 2 and 3 of the drawing. Spaced about the periphery of the apertures 14 and 15, the top 11 of the attachment is provided with upwardly pressed spaced knobs 17, upon which cooking pots or vessels are adapted to be placed, and it will be understood that the apertures 14 and 15 are adapted to register with the burners 6 and 7 of the gas stove 5, and the walls 16 of said apertures are adapted to direct the flame and heat arising from said burners to the bottom of pots or vessels placed over the apertures 14 and 15.

The flanges 12 of the attachment 10 are provided with downwardly directed members 18 which form legs, which are adapted to rest upon the top of the gas stove 5, and mounted in connection with the sides and ends of the attachment are springs 19, having hook-shaped free ends 20, which are adapted to engage the rim portions 8 of the stove 5 for securely holding the attachment 10 in position on the stove and for preventing the shifting thereof.

I also provide the walls 16 of the apertures 14 and 15 with spaced slots 21 arranged adjacent to the top 11 of the attachment and mounted in and movable in said slots, are a corresponding number of supporting mem-

bers 22, the inner ends of which are provided with downwardly directed and outwardly flared faces 23 to correspond with the flare of the walls 16, and headed pins or 5 rivets 24 are mounted in connection with the outer ends of said members and extend upwardly through elongated apertures 25 in the top 11 of the attachment as clearly shown in Figs. 1 and 3 and by means 10 of which the members 22 may be adjusted inwardly and outwardly and radially of the apertures 14 and 15. The members 22 are designed to be used for supporting small cooking pots, vessels or the 15 like over the burners 6 and 7 of the gas stove but when not in use the members 22 assume the position shown at the left of Fig. 1 of the drawing, and said members do not interfere in any way with the operation of 20 the attachment in connection with large or normal size cooking pots or vessels.

It is a well known fact that with gas stoves as commonly employed the greater portion of the heat rising from the burner or burners 25 of a gas stove is lost by radiation therefrom, and by using my improved attachment, the heat rising from the burner or burners of a gas stove may be directed to and concentrated to the cooking pot or vessel to be 30 heated, whereby the desired result is accomplished in the most efficient and economical manner, it being understood that a material saving in the consumption of fuel is thereby effected, and while I have 35 shown certain details of construction for carrying my invention into effect, it will be apparent that I am not necessarily limited to these details and various changes therein and modifications thereof may be made 40 within the scope of the appended claims without departing from the spirit of my invention or sacrificing its advantages.

Having fully described my invention, what I claim as new and desire to secure by 45 Letters Patent, is:—

1. An attachment of the class described provided with an aperture having a downwardly and an outwardly flared wall, and a plurality of supporting members adjustably mounted in connection with said attachment and movable inwardly and radially of 50 said aperture.

2. An attachment of the class described provided with an aperture having a downwardly and an outwardly flared wall, a plurality of supporting members adjustably mounted in connection with said attachment and movable inwardly and radially of 55 said aperture, and the inner ends of said supporting members being provided with downwardly and outwardly flared walls.

3. An attachment of the class described provided with an aperture having a downwardly and an outwardly flared wall, a 60 plurality of supporting members adjustably

mounted in connection with said attachment and movable inwardly and radially of said aperture, the inner ends of said supporting members being provided with downwardly and outwardly flared walls, and resilient devices for detachably mounting said attachment in connection with a suitable support. 70

4. An attachment of the class described provided with an aperture having a downwardly and an outwardly flared wall, a plurality of supporting members adjustably mounted in connection with said attachment and movable inwardly and radially of said aperture, the inner ends of said supporting members being provided with downwardly and outwardly flared walls, and the top face 75 of said attachment being provided about the periphery of said aperture with upwardly projecting members. 80

5. An attachment for gas stoves, said attachment being fashioned from sheet metal and provided with an aperture adapted to register with a burner of said gas stove, said attachment being provided around the aperture therein with a downwardly and outwardly flared wall, whereby the heat arising 90 from said burner will be directed through said aperture, the top face of said attachment being provided about the periphery of said aperture with upwardly projecting members, and supporting members adjustably mounted in connection with said attachment and movable radially of the 95 aperture of said attachment.

6. An attachment for gas stoves, said attachment being fashioned from sheet metal and provided with an aperture adapted to register with a burner of said gas stove, said attachment being provided around the aperture therein with a downwardly and outwardly flared wall, whereby the heat arising 100 from said burner will be directed through said aperture, the top face of said attachment being provided about the periphery of said aperture with upwardly projecting members, supporting members adjustably mounted in connection with said attachment and movable radially of the aperture of 105 said attachment, and the inner ends of said members being provided with downwardly and outwardly flared walls. 110

7. An attachment for gas stoves, said attachment being fashioned from sheet metal and provided with an aperture adapted to register with a burner of said gas stove, said attachment being provided around the aperture therein with a downwardly and outwardly flared wall, whereby the heat arising 120 from said burner will be directed through said aperture, the top face of said attachment being provided about the periphery of said aperture with upwardly projecting members, supporting members adjustably mounted in connection with said attachment and movable radially of the aperture of 125 said attachment. 130

attachment, the inner ends of said members being provided with downwardly and outwardly flared walls, and resilient devices for detachably supporting the attachment in connection with a gas stove.

8. An attachment for gas stoves of the class described, said attachment being fashioned from sheet metal and provided with a plurality of spaced apertures adapted to 10 register with a corresponding number of burners of a gas stove, said attachment being provided around the apertures therein with downwardly and outwardly flared walls, whereby the heat arising from the separate 15 burners will be directed through said apertures.

9. An attachment for gas stoves of the class described, said attachment being fashioned from sheet metal and provided with 20 a plurality of spaced apertures adapted to register with a corresponding number of burners of a gas stove, said attachment being provided around the apertures therein with downwardly and outwardly flared walls, 25 whereby the heat arising from the separate burners will be directed through said apertures, and the top face of said attachment being provided around said apertures with spaced projecting members.

30 10. An attachment for gas stoves of the class described, said attachment being fashioned from sheet metal and comprising a top plate having downwardly directed side and end walls and a central partition wall, 35 the top plate being provided with a plurality of spaced apertures adapted to register with the separate burners of a gas stove, said attachment being provided around the apertures therein with downwardly and outwardly flared walls, whereby the heat arising from said burners is directed through 40 the apertures of said attachment.

11. An attachment for gas stoves of the class described, said attachment being fashioned from sheet metal and comprising a top 45 plate having downwardly directed side and end walls and a central partition wall, the top plate being provided with a plurality of spaced apertures adapted to register with the separate burners of a gas stove, and the top plate being provided around the apertures therein with downwardly directed and outwardly flared walls, whereby the heat arising from said burners is directed through 50 the apertures of said attachment, and supporting members adjustably mounted in connection with the top plate and adapted to extend into the apertures therein.

55 12. An attachment for gas stoves of the class described, said attachment being fashioned from sheet metal and comprising a top plate having downwardly directed side and end walls and a central partition wall, the top plate being provided with a plurality 60 of spaced apertures adapted to register

with the separate burners of a gas stove, the top plate being provided around the apertures therein with downwardly directed and outwardly flared walls, whereby the heat arising from said burners is directed 70 through the apertures of said attachment, supporting members adjustably mounted in connection with the top plate and adapted to extend into the apertures therein, and the inner ends of said members being provided 75 with downwardly and outwardly flared walls.

13. An attachment for gas stoves of the class described, said attachment being fashioned from sheet metal and comprising a top plate having downwardly directed side and end walls and a central partition wall, the top plate being provided with a plurality of spaced apertures adapted to register 80 with the separate burners of a gas stove, the top plate being provided around the apertures therein with downwardly directed and outwardly flared walls, whereby the heat arising from said burners is directed 85 through the apertures of said attachment, supporting members adjustably mounted in connection with the top plate and adapted to extend into the apertures therein, and the inner ends of said members being provided 90 with downwardly and outwardly flared walls, and resilient members for detachably supporting said attachment in connection with a gas stove.

14. An attachment for gas stoves, said attachment being fashioned from sheet metal and provided with an aperture adapted to 100 register with a burner of said gas stove, and supporting members adjustably mounted in connection with said attachment and movable radially of the aperture 105 therein.

15. An attachment for gas stoves, said attachment being fashioned from sheet metal and provided with an aperture adapted to register with a burner of said gas stove, supporting members adjustably mounted in connection with said attachment and movable radially of the aperture therein, and means 110 for detachably supporting said attachment in connection with the gas stove.

115 16. An attachment for gas stoves of the class described, said attachment being fashioned from sheet metal and comprising a plate having downwardly directed side and end walls, the top plate being provided with a plurality of spaced apertures adapted to 120 register with the separate burners of a gas stove, and supporting members adjustably mounted in connection with the top plate and movable radially of the apertures 125 therein.

In testimony that I claim the foregoing as my invention I have signed my name this 7th day of Dec., 1922.

JAMES G. WILKIE.
